UNITED STATES PATENT OFFICE.

WALTER EICHELKRAUT, OF ZEHLENDORF, NEAR BERLIN, GERMANY.

CLOSET.

1,016,001.

Specification of Letters Patent. Patented Jan. 30, 1912.

Application filed November 14, 1911. Serial No. 660,245.

To all whom it may concern:

Be it known that I, WALTER EICHELKRAUT, a subject of the King of Prussia, and resident of 6/8 Seehofstrasse, Zehlendorf, near Berlin, Germany, architect, have invented 5 certain new and useful Improvements Relating to Closets, of which the following is a specification.

This invention relates to closets having a 10 plurality of interchangeable seats, and the object of the present invention is to provide means whereby the seats may be successively passed through an antiseptic liquid for the purpose of cleansing, disinfecting and sterilizing the same.

According to the present invention the seats, which are preferably made in two halves, are carried by arms at each side of the closet basin, these arms being mounted 20 upon a rotatable shaft in the rear of the basin. The halves of the seats are rotatably mounted on their arms so as to be capable of assuming a vertical position when not in use. A chamber adapted to contain an antiseptic liquid is arranged at each side of the basin and the action of bringing the next seat into position for use, is utilized to immerse the used seat into the antiseptic liquid. Four arms are preferably arranged 25 at right angles to each other at each end of the shaft, each arm being adapted to carry one half of a seat and the antiseptic liquid chamber is preferably of semicircular form, so that the operation of immersing one seat 30 at right angles to each other at each end of the shaft, each arm being adapted to carry one half of a seat and the antiseptic liquid chamber is preferably of semicircular form, so that the operation of immersing one seat 35 in the liquid simultaneously withdraws another seat from the liquid and enables said seat to dry. In order to facilitate the drying of the seats during the interval of time between their withdrawal from the antiseptic liquid and the bringing of the seat into 40 position for use, the antiseptic liquid is preferably heated so as to more readily vaporize from the seat.

In order that the invention may be more 45 clearly understood, reference is made to the accompanying drawings, whereon I have shown by way of example one method of carrying out my invention.

Figure 1 is a front view of the apparatus, 50 Fig. 2 is a plan view, and Fig. 3 a side view thereof.

1 designates the closet basin provided in the rear with brackets 9 in which is rotatably mounted a horizontal shaft 2. At each 55 end of said shaft are carried a plurality of arms 3, four being shown on the drawings

arranged at right angles to one another. Rotatably mounted on each of the arms 3 is one half of a seat 10, the seat being shown on the drawings as provided with lugs 11 loosely fitted upon the arms 3. In order to normally maintain the seats in vertical position, a crown-shaped cam 5 is mounted on the brackets 9, and adapted to engage with this cam 5 is a wiper 4 shown on the drawings as fixed to the half 10 of the seat. The wiper 4 is maintained in engagement with the face of the cam 5 by means of a spring 6, one end of which is secured to the arm 3, while the other end bears against the side 70 face of the wiper 4. The rear half of the face of the cam 5 is perfectly straight and vertical so that under the action of the spring 6 and wiper 4 the half 10 of the seat is maintained in vertical position during the 75 rear half of its rotation. The forward half of the face of the cam is provided with a depression 7 so that the seat on maintaining its highest position in readiness for bringing it into use, is enabled to assume a horizontal position and rest on the basin on further rotation of the shaft 2. The lower front half of the face of the cam 5 is outwardly curved at 7' so that the action of bringing a seat into use causes the wiper 4 of the seat 80 previously used to ride on the cam surface 7' and turn the half 10 of the used seat into vertical position.

Arranged at each side of the closet basin 1 is a substantially semi-cylindrical chamber 8 adapted to contain an antiseptic liquid, and the halves 10 of the seats are adapted to move through this chamber during the lower half of their rotation, while they are capable of drying during the upper half of their 95 rotation. The seats are adapted to be rotated in the direction of the arrow A in Fig. 3 about the shaft 2 and in order to prevent return movement of the shaft 2, a ratchet wheel 12 fixed thereon is adapted to be engaged by means of a spring pawl 13 mounted on the bracket 9.

In order to facilitate the drying of the seats, the liquid in the chamber 8 may be heated in any desired manner. On the 105 drawings I have shown an electrical resistance 14 located in the lower part of the chamber 8 and adapted to be connected with suitable electrical connections, but it will of course be understood that the liquid in the 110 chambers 8 may be heated in any other desired manner. In order to prevent the es-

cape of fumes from the chamber 8 the latter may be provided with hinged flaps 15 hinged to the top of the chamber 8 at 16 so as to be capable of opening inwardly. The heating 5 of the antiseptic liquid in the chamber 8 not only facilitates the drying of the seat, but also serves to slightly heat the same, which is particularly advantageous when the seats are constructed of porcelain or like mate-
10 rial. The seats may however be constructed of any desired material. When employing wood seats it is preferable that resinous wood be employed or that the wood be boiled in varnish and be not capable of
15 warping in the liquid.

I claim:—

1. In combination with a closet basin, a horizontal rotatable shaft, a plurality of seats carried by said shaft and normally held in a vertical plane, means whereby said seats may be successively moved into the horizontal plane so as to rest on said basin and a chamber through which said seats are adapted to be moved when in vertical position, said chamber containing an antiseptic liquid.

2. In combination with a closet basin, a horizontal rotatable shaft, a plurality of divided seats, arms at each end of said shaft, 30 said arms rotatably carrying the respective portions of said seats, means for normally maintaining said seat portions in vertical position and whereby said seat portions may be successively moved into horizontal position so as to rest on said basin, and a chamber at each side of said basin through which said seat portions are adapted to be moved when in vertical position, said chambers containing an antiseptic liquid.

40 3. In combination with a closet basin, a horizontal rotatable shaft, a plurality of divided seats, arms at each end of said shaft, said arms rotatably carrying the respective portions of said seats, means for normally

45 maintaining said seat portions in vertical position and whereby said seat portions may be successively moved into horizontal position so as to rest on said basin, and an approximately semicylindrical chamber at each side of said basin and somewhat below 50 said shaft and containing an antiseptic liquid, said seat portions being adapted after use to be moved through said liquid in a vertical position and during the lower part of their movement and being capable 55 of drying during the upper part of their movement ready for re-use.

4. In combination with a closet basin, a horizontal rotatable shaft, a plurality of seats carried by said shaft and normally held in a vertical plane, means whereby said seats may be successively moved into the horizontal plane so as to rest on said basin, a chamber through which said seats are adapted to be moved when in vertical position, said chamber containing an antiseptic liquid, and means for heating the liquid in 60 said chamber.

5. In combination with a closet basin, a horizontal rotatable shaft, a plurality of 65 seats carried by said shaft and normally held in vertical plane, means whereby said seats may be successively moved into the horizontal plane so as to rest on said basin, a chamber through which said seats are 70 adapted to be moved when in vertical position, said chamber containing an antiseptic liquid, means for heating the liquid in said chamber, and hinged flaps adapted to prevent the escape of fumes from said chamber 75 while enabling the seats to be moved there- 80 through.

In witness whereof I have hereunto set my hand in the presence of two witnesses.

WALTER EICHELKRAUT.
